DISPENSING NOZZLE

Emerson H. Tompkins and John H. Tobler, Waterbury, Conn., assignors to Scovill Manufacturing Company, Waterbury, Conn., a corporation of Connecticut

Application May 15, 1937, Serial No. 142,844

6 Claims. (Cl. 251—134)

This invention relates to dispensing nozzles, and particularly to that type of nozzle found in general use for dispensing gasoline at service stations.

One of the principal objects of this invention is to provide a nozzle construction in which the body part of the nozzle will possess three features; one, a direct line of flow from the supply to the delivery; second, a particularly effective and precise control of flow when only small quantities are required; and third, an exterior form which will offer a convenient grasp to the operator as well as a symmetrical contour with no irregularities beyond the classic form of trigger and trigger guard long associated with manually operated controls. These features are, more specifically, effected by a valve construction wholly contained within the tubular section of the body, and at the same time creates a nozzle with an attractive contour or artistic balance harmonious with the more modernistic trend of service station design.

A further object is to provide a straight flow nozzle of the above nature in which the body part serves as a hand gripping portion for operating the valve control handle, and the motion of the handle in turn is transmitted to the interior of the casing to actuate a valve by means of an entirely enclosed bell crank lever and an exteriorly projecting plunger pin.

A still further object is to provide a liquid flow control means to operate in conjunction with the control valve for the purpose of preventing the annoying hammering or chattering effect of the control valve when slowly opening the valve for the purpose of drawing off a small quantity of liquid or when slowly closing off the valve just prior to the complete shut-off of the nozzle in approaching the predetermined amount of liquid to be dispensed.

Other objects and advantages of this invention will be apparent and more clearly understood from the following description which, taken in connection with the accompanying drawing, discloses a preferred embodiment thereof.

In the drawing:

Fig. 1 is a front elevation of the dispensing nozzle, shown attached to a delivery hose and a discharge spout, and embodying the principles of the invention.

Fig. 2 is a longitudinal sectional view through the same on an enlarged scale, with the valve in closed position.

Fig. 3 is a transverse sectional view through

the nozzle taken along the broken line 3—3 of Fig. 2, looking in the direction of the arrows.

Fig. 4 is an enlarged side elevation of the flow regulator shell, per se.

Fig. 5 is a perspective view of the valve stem 5 guide member, per se.

Referring to the drawing by reference characters in which like numerals designate like parts throughout the several views, the numeral 10 designates generally the nozzle body, comprising a relatively straight tubular portion 11 having a slightly enlarged tapped rear end 12 for receiving a coupling connecting nut 13. The connecting nut 13 permits the nozzle 10 to be conveniently attached to the conventional form 15 of liquid conduit hose 14 having the usual terminal coupling connection 15.

The forward end of the nozzle body 10 is provided with an interiorly reduced threaded part 16 for detachably receiving a discharge spout 17 20 by means of an intermediate connecting nut 18. While the spout 17 is here shown as being made of rigid tubing, it is to be understood that the flexible type of tubing may be used equally well within the spirit of the invention.

The interior of the tubular portion 11 is divided by an intermediate partition wall 19 which serves to divide the tubular portion 11 into two separated chambers 11a and 11b. The partition wall 19 is provided with a direct opening or fluid passage 20 concentric with the bore of the tubular portion 11 and a beveled valve seat 21. The fluid passage 20 is controlled by a sealing washer 22 of the nature of a poppet valve preferably made of a non-metallic composition, such as 35 "Thiokol", which substance is resistant proof against the solvent characteristics of gasoline. The sealing washer 22 is supported in a cupped disc 23, both parts of which surround a reduced portion 24a of a valve stem 24 disposed coaxially within the hollowed chamber of the nozzle body 10. Seated against the forward face of the sealing washer 22 is the base end of a flow regulator cylindrical shell 25, and all of the parts, 22, 23 and 25 supported by the reduced portion 24a, are adapted to be tightly clamped against a shoulder 24b on valve stem 24 by means of a clamping nut 26.

In order to control the volume of liquid passing through the fluid passage 20 under pressure incidental to the slow opening and closing operation of the valve without danger of producing a hammering or chattering effect, the flow regulator shell 25 is provided with a plurality of specially shaped openings or holes 27 about its 55

peripheral wall. The forward part of these openings, as best viewed in Fig. 4 are made substantially square or rectangular shaped 27a and converge into gradually restricted portions 27b, the purpose of which will be more fully described later. While there are only four of these special shaped openings 27 shown in the shell 25, it is obvious that the size and number of these openings may be varied to suit the requirements of the particular nozzle to which the shell may be applied without essentially affecting the operation and still accomplish the same results.

From an inspection of Fig. 2, it can be seen that the regulator shell 25 further serves as a support bearing or guiding means for the forward end of the valve stem 24 with respect to the partition wall 19. The rear end of the stem 24, in turn, is associated with a spider-like support 28 provided with appropriate fluid passages 28a and adapted to be threadedly engaged into the extreme base part of the threaded enlarged section 12 of the nozzle 10. The spider support 28 is formed with a concentric guide sleeve 28b for slidably receiving and supporting the adjacent end of the valve stem 24. A coiled compression spring 29 surrounds the valve stem 24 and is interposed between the washer support shell 23 and the spider support 28 and forms a means for normally holding the valve washer 22 in closed seated position against the partition 19.

In order to provide convenient means for actuating the valve, the forward and rear ends of the nozzle body 10 are formed with relatively short and long projections 30 and 31 respectively, depending integrally from the lower part of the body 10. The forward short projection 30 is provided with a bifurcated end 33 for hingedly receiving one end of a valve actuating trigger or handle 34 by means of a fulcrum pin 35. The opposite end of the handle lever 34 is disposed and guided in a vertical slot 36 cut out of the long depending rear projection 31. In order to define the space in which the lever 34 operates, provision is made of guard member 37 having its forward and rear ends connected to the short and long projections 30 and 31 respectively, as by means of screws 38.

The swinging motion of the handle 34 when operated is adapted to be transmitted to actuate the valve washer 22 and associated parts by means of a plunger pin 39 and a bell crank lever 40. More specifically, the bell crank lever 40 is entirely enclosed within the forward hollow chamber 11a of the tubular portion 11 and is provided at one end with an enlarged bearing 41 hingedly supported on a transverse pin 42. This pin 42 is seated in a suitable socket 10b provided in an embossed part 10a of the body 10. The transverse pin 42 is removably retained in the socket 10b by means of a socketed nut 44, threadedly engaged in a tapped hole 45 in the embossed part 10a, all as best shown in Fig. 3. The tapped hole 45 is preferably of a tapered or pipe threaded construction to prevent leakage. The opposite end of the bell crank lever 40 is provided with a cam head 46 engaging against a headed insert pin 47 affixed to the further reduced end 24c of the valve stem 24. This pin 47 is made of metal material of a harder composition than either the bell crank 40 or the stem 24 for the purpose of effecting greater wear resistance between the working parts.

The plunger pin 39, previously mentioned, has its axis disposed substantially at right angles to the axis of the body tubular portion 11 and is

slidably engaged in a projecting boss 48 depending from the lower part of the body 10 adjacent the short projection 30. The slidably connector of the pin 39 within the boss 48 is rendered liquid proof by means of a packing 49 surrounding said pin 39 and compressed in a pocket 50 provided in the boss 48 by means of a gland sleeve 51 and a cooperative bonnet nut 52 engaging the exterior threaded part of the boss 49. The exterior surface of the nut 52 is provided with a relatively heavy straight line knurl to facilitate the operation of the same.

More specifically, the particular construction of the gland sleeve 51 is such as to produce a more efficient and rigid slidable bearing construction between said gland 51 and the plunger pin 39. This is produced in providing an intermediate surrounding hub 51a on the gland sleeve 51 adapted to have frictional rotatable abutted engagement with the interior surface of said nut 52. This gland sleeve 51 is then formed with an extended portion 51b projecting through and beyond a corresponding aligned opening in the nut 52, and perforce embraces a longer section of the pin 39 than was possible with the ordinary conventional gland construction. An inspection of the above device further reveals that there is no chance for the nut 52 to come into wearing contact or engagement with the plunger pin 39 and consequently precludes any harmful wearing effects upon said pin 39.

Motion is transmitted from handle 34 to bell crank 40 through pin 39 wherein the interior end of the plunger pin 39 engages the bell crank lever 40 and the exterior end of the pin outside of the body 10 engages with the angular face of an embossed part 34a integral with the handle 34.

In order to operate this dispenser nozzle, the device is grasped in the natural manner with the body 10 of the nozzle disposed in the palm of the operator's hand, permitting his fingers to embrace the straight section of the hand lever 34.

The nozzle may then be conveniently carried to a container to be filled, after which the lever 34 is moved toward the body 10 by the fingers of the operator. This operation results in moving the plunger pin 39 inwardly which causes the bell crank to pivot within its respective chamber 11a and move the valve stem rearwardly or to the right as viewed in Fig. 2 in a linear direction against the resistance of the spring 29. This linear movement of the plunger 24 will perforce carry the sealing washer 22 and flow regulator shell 25 with it to uncover the valve seat 21 for permitting a flow of fluid from the chamber 11b through chamber 11a out through spout 17. When it is desired to shut off the flow, the pressure of operator's fingers is released from the lever 34, whereupon the spring 29 closes the valve and returns the intermediate linkage (bell crank 40, plunger pin 39) and handle lever 34 back to normal position.

When it is desired to control the flow of fluid through the nozzle with a finer precision, the valve washer 22 may be retained in a partially open position by imparting a slight movement to the lever 34. The initial uncovering of the washer 22 from the seat 21 causes the liquid to exert backward pressure on the valve face of the washer 22 due to the fact that liquid is not permitted to flow through the opening 20 in the partition wall 19 until such time as the more constricted portion 27b of the opening in the shell 25 clears the bevel seat 21. This initial backward pressure on the washer 22 conduces to

prevent the chattering or hammering of the valve that is prevalent in a construction where the flow of fluid is unobstructed at the instant the valve is opened or closed.

5 Since the regulator shell 25 has a relatively close sliding fit in the partition fluid passage 20, the fluid must necessarily first pass inwardly through the more constricted portions of the converging part 27b of the openings 27 in shell 25 when the valve is first opened, and the flow of liquid is proportionately increased through the nozzle as the shell 25 is progressively moved to the right to cause a relatively greater area of the openings 27 to clear by the valve seat 21. Obviously, in shutting off the nozzle, the flow of fluid will be progressively decreased to a degree much more than proportional to the movement of the lever, so that a small amount of flow can be effected by the operator to arrive at the exact 20 quantity of fluid desired, since the acute angle of the feeding end 27b of the opening 27 brings a rapidly lessening area of flow into cooperation with valve seat 21 of the partition wall 19.

While only one form of the invention is presented herein for the purpose of exemplification, it will be appreciated that the invention is susceptible of embodiment in other structurally modified forms coming equally within the scope of the appended claims.

30 What is claimed is:

1. In a dispensing device, a substantially tubular shaped body designed to serve as a handle to manipulate the device, an intermediate partition wall within said body having a fluid orifice 35 and adapted to divide the hollow interior of said body into two separated fore and rear chambers, a spring operated valve means coaxially mounted within said body for closing said orifice, a pair of brackets integral with and depending from 40 the fore and rear ends of said body, a handle lever pivoted to said fore bracket and having a guiding connection in said rear bracket, and linkage means connecting said valve means with said lever to operate said latter means in one direction, said linkage means comprising a bell crank located in the fore chamber and a plunger pin extending outside of said body and operated from an intermediate portion of said lever.

2. In a dispensing device, a tubular shaped body designed to serve as the gripping handle for manipulating the device, an intermediate partition wall within said body having a fluid orifice and adapted to divide the hollow interior of said body into two separated fore and rear chambers, a spring operated valve means coaxially mounted within said body for closing said orifice, a pair of brackets integral with and depending from the fore and rear ends of said body, a handle lever pivoted to said fore bracket, said rear bracket having a longitudinal slot serving as a guide for the free end of said handle, an integral hollow boss projecting from the body between and in the plane of said brackets at an

axis substantially perpendicular to the principal axis of said body, a bell crank hingedly mounted in said fore chamber and having opposed cam faces, and a plunger pin slidably mounted in said boss and having its inner end slidably engaging one of said cam faces and its outer end slidably engaging an intermediate portion of said handle. 5

3. In a dispensing device, defined as in claim 2, wherein an adjustable stuffing box is associated with said boss to effect liquid tight sliding fit with said plunger pin, and a handle guard is connected between the depending brackets for defining the space in which the handle lever operates. 10

4. In a dispensing device, a tubular shaped casing having a hollow interior for permitting substantially a straight flow of fluid therethrough, said casing designed to form the handle by which the device is held and manipulated, 20 a partition wall having a restricting orifice and serving to divide said hollow interior into fore and rear chambers, a valve stem coaxially disposed in said rear chambers, a spring operated poppet valve carried by said stem for normally 25 closing said orifice, a bell crank disposed in said fore chamber and having a cam head engaging the adjacent end of said stem, a pin transversely mounted in said body to which said bell crank is hingedly connected, means including a stuffing box depending from said casing, a plunger pin extending through said stuffing box and disposed substantially at a right angle to the axis 30 of said casing, and handle means mounted exteriorly of said casing adapted to operate in the 35 path of said plunger pin and having means at its intermediate portion to engage said pin and transmit motion to said valve stem through said bell crank and plunger pin.

5. In a dispensing device defined as in claim 4, wherein said transverse pin is removably mounted in said casing to permit removal of said bell crank for repair and/or assembly purposes.

6. In a dispensing device a hollow body member comprising a relatively straight tubular section adapted to permit a straight flow of fluid therethrough and serving as a handle means for said device, a valve means, a supporting member for said valve means disposed entirely within said body and movable coaxially therewithin, 45 a plunger pin passing out of said body transversely to the axis of said body, a bell-crank pivotally mounted within said body and having angularly disposed cam face for slidably engagement against the adjacent ends of said pin and supporting member respectively, and a handle lever pivoted outside of said body and adapted to be swung inwardly toward said body transmitting motion to said valve through said intermediate 50 plunger pin and bell-crank. 60
